UNITED STATES PATENT OFFICE.

FRANK G. HANBACK, OF ALLEGANY, NEW YORK.

GAME.

Application filed September 24, 1923. Serial No. 684,585.

To all whom it may concern:

Be it known that I, FRANK G. HANBACK, a citizen of the United States, residing at Allegany, in the county of Cattaraugus and 5 State of New York, have invented certain new and useful Improvements in Games; and I do declare the following to be a full, clear, and exact description of the invention, such as will enable others skilled in the art 10 to which it appertains to make and use the same.

This invention relates to an improved game of the type possessing educational and amusing features and it has been my primary 15 aim in producing this game to widen one's memory, to develop concentration of mind and to provide wholesome amusement for both the young and old.

More specifically speaking, the game is 20 one, which upon manual manipulation, presents to view in an indeterminate manner, one or more of a number of symbols or characters which may be individually, successively or unitedly coupled to produce varied 25 and entertaining results to accomplish the ends above enumerated.

It is also a feature of the invention to provide a game of this type embodying relatively stationary and movable parts, one 30 of which is provided with symbols or characters on both faces and the other one of which is provided with openings through 35 which these symbols are exposed to view, both of said parts being reversible and co-acting in a manner so that varied combinations and results can be accomplished.

Other features and advantages of the invention will be apparent from the following description.

40 In the accompanying drawings forming a part of this specification and in which like numerals are employed to designate like parts throughout the same:

Figure 1 is a top plan view of a game 45 constructed in accordance with the invention.

Figure 2 is a sectional view taken on the line 2-2 of Fig. 1.

Figure 3 is a top plan view of the relatively stationary base plate showing one side thereof.

Figure 4 is a like view showing the opposite side of the base plate.

In carrying out the invention, I employ a substantially square stationary base 1 which has its faces ornamented in any ap-

propriate way to give it an artistic appearance. Of course, the shape of this base is immaterial and it may be of any desirable contour. As seen more clearly in Figs. 2 60 and 3, the opposite sides of this base are provided with a plurality of varying symbols 2 which may, in practice, be of any appropriate form. For instance, as seen in Fig. 3, the symbols are in the form of 65 letters arranged singularly or together. The symbols of this character permit the formation of words, phrases and sentences when combined in different manners as will be more clearly apparent from the following 70 description. On the other side of the board I have shown numbers in groups and single, these groups having suffixes and prefixes associated therewith to vary their values. These two views simply represent two different types of symbols which may be employed, and, it is to be understood that the symbols could well be in the form of figure simulations of animate or inanimate beings. The kinds of symbols employed on the base 80 board are immaterial so far as the invention is concerned. It may be well to disclose the fact that these symbols or characters are by preference arranged on lines forming graduated concentric circles. Several characters 85 are also arranged in alignment with one another on lines radiating from the axis of the base.

Pivots mounted on the base and adapted for rotation with respect thereto is a disk 3 90 of cardboard or any other suitable material, the same being pivotally connected with the base by a removable fastening or pivot pin 4. To resist wear at the points where the pivot pin passes through the disk and base, 95 these parts are equipped with metal ferrules 5. It is to be noted that the disk 3 is equipped with a plurality of apertures or openings 6 which are arranged at predetermined points and are adapted for coaction 100 with the aforesaid symbols to render the latter visible therethrough for permitting the formation of the words etc. These apertures are arranged on lines radiating from the axis of the disks and may be 105 arranged in pairs or singularly to expose one or more of the symbols on the radial line of the base over which they are positioned. Hence, varied combinations can thus be produced and the result can be rendered more or less indeterminate. It is of course understood that in play, the disk is 110

simply manually rotated and allowed to stop to expose the characters through the apertures. It often happens however that the openings or apertures do not stop directly over the characters which they are intended to expose and it becomes necessary to provide means for securing alinement. Although the means desired could be of any other construction, I simply extend the radial lines on which the symbols are arranged on the base plate beyond the periphery of the disk to provide circumferentially spaced stopping points 7. For cooperation with these stopping points I depict a stopping arrow 8 on the disk. When this arrow is alined with one of the stopping points 7, the symbols on the base plate will be fully exposed through the aperture in the disk.

As before indicated, in playing the game each person spins the disk 3 and permits it to stop of its own accord. If the apertures in the disk do not stop directly over the characters or symbols on the base plate, it is within the rules of the game to move the disk to bring arrow 8 in alinement with the stopping point 7 to which it is then closest. Hence, the openings 6 will be alined with the symbols 2 and the next step is to combine the symbols to obtain the desired result. For instance, if letters form the symbols, it will be the point to combine the letters to form as many words as possible. If the symbols are in the form of simulations of human beings, these will, in practice, be suffixed or prefixed with minus and plus signs, the plus sign indicating that the figure has been captured and the minus sign indicating that it has escaped. The same is true when the symbols are in the form of figures, that is, the figures are added together to obtain the greatest total possible. After a predetermined number of spins has been made by each contestant, a grand total is obtained and the winner is announced. Of course, the rules of the game will vary with the circumstances encountered.

It is a particular advantage of the inven-

tion, as before pointed out, in providing symbols on both sides of the base plate to permit reversal thereof to obtain a varied result and it is likewise important to remember that since the openings in the rotay disk are at predetermined points, it is also capable of being reversed to obtain different problems to be solved.

Although the preferred embodiment of the invention has been specified, it is to be understood that minor changes in shape, size and arrangement of parts may be resorted to within the scope of the joint claims.

I claim:

1. A game comprising a relatively stationary base having symbols depicted thereon at predetermined intervals, a rotary disk associated with said base, said disk having apertures formed therein at predetermined points adapted for coaction with said symbols to expose the latter therethrough, circumferentially spaced stopping points arranged on said base, and an indicating arrow on said disk cooperable with said stopping points for aligning said apertures with said symbols.

2. A game comprising a relatively stationary base having on its opposite faces a plurality of symbols arranged in radial rows, the symbols on one face differing in character from those on the other face, a series of radial stopping points on said opposite faces of the base, one of said points being disposed at the end of each radial row of characters, a removable pivot pin secured in said base, a disc mounted for rotation on said pin and spaced a slight distance from said base, said disc having apertures formed therein at predetermined points and through which the characters on said base are exposed and an arrow arranged on said disc to cooperate with the stopping points on said base for aligning said apertures with said symbols.

In testimony whereof I have hereunto affixed my signature.

FRANK G. HANBACK.
